(57) **CLAIM**

The ornamental design for a merchandising hanger, as shown and described.

DESCRIPTION

FIG. 1 is a perspective view of a merchandising hanger, showing my new design;
FIG. 2 is a front elevation view thereof;
FIG. 3 is a rear elevation view thereof;
FIG. 4 is a left-side elevation view thereof, the right side being a mirror image thereof; and
FIG. 5 is a top plan view thereof, the bottom view the same in appearance; and,
FIG. 6 is a perspective view of a second embodiment of FIG. 1, the only difference being the slots, it being understood that all other surfaces are the same as those of the first embodiment.
